ROLL STAND FOR FLYING SPLICES

James P. Van Dusen, Richmond, Va.

Application August 14, 1952, Serial No. 304,248

5 Claims. (Cl. 242—75)

1

It is an object of this invention to provide an improved apparatus for carrying out the method disclosed and claimed in my copending application Serial No. 257,552, filed November 21, 1951.

It is a further object of this invention to adapt for the most part the apparatus now most generally in use in bag factories to the performance of the improved method.

The above and other objects will be made clear from the following detailed description taken in connection with the annexed drawings, in which:

Figure 1 is a side elevation view;

Figure 2 is a partial front elevation view of the improved apparatus; and

Figure 3 is a view similar to Figure 1 showing a modification of the structure of the lower right hand corner of Figure 1.

As noted in my copending application aforesaid, heretofore when a flying splice has been attempted either on a bag machine or a printing press, it has been considered necessary to effect a bodily movement either of the exhausted roll or of the replenishing roll. The present invention contemplates fixed bearings in which either of two rolls may act as the replenishing roll.

Referring to the drawings, there is shown a side frame member 10, one of such members being provided on each side. At the top of the frame there is a notch 12 and adjacent the bottom of the frame a notch 14. The upper notch 12 is adapted to receive a shaft 16 on which is centered a roll of paper 18. The notch 14 is adapted to receive the shaft 20 of another roll of paper 22.

Keyed to the upper shaft 16 is a pinion 24 which meshes with a gear 26 mounted on a shaft 28. A brake drum 30 is similarly keyed to the shaft 28 and is contacted by a brake shoe 32 influenced on one side by a rod 34 and on the other side by a rod 36.

A pinion 38 is keyed to the lower shaft 20 and meshes with a gear 40 keyed to a shaft 42. A brake drum 44 is keyed to the shaft 42 and has bearing on a brake shoe 46. The brake shoe 46 is controlled on one side by a rod 48 and on the other side by a rod 50, the rods 48 and 50 being crossed. The rod 48 runs from the lower brake shoe 46 to a member 52 in which it is secured by adjustable nuts 54. The rod 34 runs from the upper brake shoe 32 to the opposite end of the member 52 where it is secured by adjustable nuts 56. The member 52 is mounted on an eccentric 58 on a shaft 60. The shaft 60 and the

2

eccentric 58 may be rotated by means of a handle 62. In the position illustrated in Figure 2 the member 52 is in its lowermost position, relieving tension on the lower brake shoe 46 and applying tension to the upper brake shoe 32.

The rod 50 connects the opposite side of the lower brake shoe 46 to one arm 64 of a bell crank 66 mounted on a shaft 68. A rod 36 connects one end of the upper brake shoe 32 to the opposite arm 70 of the bell crank 66.

Bell crank 66 is keyed to the shaft 68 and spaced pairs of elongated arms 72 are similarly keyed to the shaft 68 and at their opposite ends carry a "dancing roll" 74. A pair of arms 76 are rotatably mounted on the shaft 78 of the dancing roll 74. The arms 76 pass through members 80 which have rollers 82 bearing on one side of the arm 76 and a roller 84 bearing on the opposite side. The members 80 are mounted for free oscillation on a shaft 86 on which is also mounted a guide roll 88.

Let us assume that a web 90 is being drawn from the upper roll 18. It passes over a guide roll 92, thence over a second guide roll 94 and a third guide roll 96. The axes of rolls 92 and 94 lie substantially in the same horizontal plane. The axis of the roll 96 is parallel to the axes of rolls 92 and 94 but lies in a lower horizontal plane. The web 90 then passes upwardly over a fixed guide roll 98 journaled in the frame 10, thence over the dancing roll 74 and thence over a guide roll 102 mounted on the shaft 86. Any change in tension in the web 90 will raise or lower the dancing roll 74 and thus will rock in one direction or another the bell crank 76 and as the tension increases and the dancing roll moves upwardly it will lift the rod 36 and relieve tension on the brake band 32. Conceivably if the tension decreases the dancing roll 74 will drop, rock the bell crank 66 clockwise and thus through the rod 36 increases the tension in the brake band 32.

If the handle 62 be rotated to its lower position the brake band 32 will be disabled and the rocking of bell crank 66 will then throughout the rod 50 adjust the tension of the brake band 46 to maintain substantially constant tension in the web 90.

Assume now that the roll 18 is approaching exhaustion: a fresh roll 22 is placed with its shaft 20 in the lower slot 14 of the frame 10 and a certain amount of slack (from one to three feet) is run off as a web 110. The leading end of the web 110 is coated with adhesive and 55 is fed over a metal feed guide 112 adjacent the

guide roll 92. After it is fed over the guide 112 it comes in contact with the trailing end of the web 90. The rolls 92, 94 and 96 form a sort of "snubber" which prevents sliding of one web on the other. As the web 110 makes contact with the web 90, the operator with a knife, or other tool, cuts the web 90 adjacent the upper roll 18 and throws the handle 62 to its opposite position to disable the brake band 32 and to place the brake band 46 in operation as a tension governing means.

Similarly when the lower roll 22 approaches exhaustion a fresh roll 18 is placed with its shaft 16 in the upper notch 12. A similar amount of slack is generated in the web 90 and the left side of its leading edge is dobb'd with adhesive. This leading end is then fed between the web 110 and the guide roll 92, at which time the web 110 is severed and the handle 62 again reversed.

The organization just described applies to a one-ply bag. However, it is perfectly possible to place in tandem relationship as many frames 10 as may be desired to handle two, three or more plies.

Frames such as 10 are very common throughout the bag making industry, for which reason only the most minor alterations are necessary to enable a flying splice to be made on existing bag machines in accordance with this invention.

No particular timing is required to generate the necessary slack in the replenishing web and to apply the adhesive. The operator must have reasonably good timing in the severing of the exhausted web and in reversal of the handle 62. This, however, has proved to be an operation easily learned and mastered.

In some cases where the webs to be spliced are not only highly impervious but also very "slick" in finish, e. g., moisture proof cellophane, it may be admissible to resort to the expedient shown in Figure 3. Here a roll 130 is journaled generally above the roll 92 in an extension 11 of the frame 10. A second roll 132 is mounted in the extension 11 generally above the roll 96. A belt 134 runs from the roll 130 over the roll 92 where it underlies the web or webs being spliced. It then passes upwardly and over the intermediate roll 94, where it overlies the web. Thence it passes downwardly and around the roll 96 where it underlies the web.

It then passes upwardly over the roll 132 and back to the roll 130.

At the lower left side of Figure 1 there are shown guide rolls 114 and 116 vertically separated with their axes parallel. At the right hand end of Figure 1 are shown guide rolls 118 and 120 similarly vertically spaced with their axes parallel. These provide for flexibility of the machine which may be placed, for example, between a printing press and a bag machine. The dotted lines and arrows indicate the various routes by which the webs can be threaded.

I claim:

1. A roll stand comprising: a pair of spaced frame members, each of said frame members having vertically spaced notches to receive the shaft of a supply roll, one of said members having a brake drum journaled adjacent each of said notches, each of said brake drums having means to engage the shaft of a supply roll to be rotated thereby, a brake shoe for engagement with each of said drums, an element mounted on said frame member intermediate said drums, means for connecting one end of each brake shoe to said element, and means for shifting the element alternately toward either of said brake shoes, whereby to disable the shoe toward which the element shifts, a bell crank mounted in said frame member, means connecting the opposite end of each of said brake shoes to one of the arms of said bell crank, a lever for oscillating said bell crank and a tensioning roll rotatably mounted in the free end of said lever.

2. A roll stand as set forth in claim 1 including means to limit the oscillation of said lever.

3. A roll stand as set forth in claim 1 including a plurality of juxtaposed guide rolls having their axes below and laterally removed from the axes of said brake drums.

4. A roll stand as set forth in claim 3 including a guide plate leading to the first of said guide rolls.

5. A roll stand as set forth in claim 4 including means to limit the oscillation of said lever.

JAMES P. VAN DUSEN.
